His Attorney.

UNITED STATES PATENT OFFICE

JOHN E. McCUAULLEY, OF NEW YORK, N. Y., ASSIGNOR TO THE UNION SWITCH & SIGNAL COMPANY, OF SWISSVALE, PENNSYLVANIA, A CORPORATION OF PENNSYLVANIA

ELECTROPNEUMATIC INTERLOCKING

Application filed February 19, 1929. Serial No. 341,251.

My invention relates to railway interlocking of the electropneumatic type, and particularly to apparatus for controlling an electropneumatic switch operating mechanism from a distant point.

I will describe one form of apparatus embodying my invention, and will then point out the novel features thereof in claims.

The accompanying drawing is a diagrammatic view showing one form of electropneumatic interlocking apparatus embodying my invention.

Referring to the drawings, the reference character A designates a railway switch which is moved to its normal and reverse positions by a switch operating mechanism B comprising a normal magnet N, a reverse magnet R, and a lock magnet L. This mechanism may, for example, be of the type shown in Letters Patent of the United States No. 1,202,164, granted to J. P. Coleman on October 24, 1916, although the specific form of switch actuating mechanism forms no part of my present invention. It is sufficient to say that when the normal magnet N and lock magnet L are energized, the switch is moved to its normal position; when the reverse magnet R and lock magnet L are energized, the switch is moved to its reverse position; and the switch operating mechanism is locked at all times except when the lock magnet L is energized.

The switch mechanism B is controlled by a manually operable lever F, which may, for example, be one of a group of similar levers in an interlocking machine. This lever is provided with normal contacts N and reverse contacts R. The switch mechanism is also controlled in part by an indication relay E which is responsive to reversals of the polarity of the current with which it is energized. This relay is provided with a circuit which includes a battery D, and a pole-changer C operated by the switch A, so that the relay is energized in the normal direction when the switch is in its normal position, and in the reverse direction when the switch is in its reverse position. Relay E is provided with a neutral contact 1 and a polar contact 2.

As shown in the drawing, the normal mag-

net N is energized, whereas the reverse magnet R and the lock magnet L are both de-energized, so that the switch A occupies its normal position. Assuming now that lever F is reversed, the circuit for the normal magnet N will become opened at the lever contact N^A, and the circuit for reverse magnet R will become closed at lever contact R^A, the circuits for these magnets being obvious from the drawing. Lock magnet L will also become energized by virtue of a circuit which passes from the left-hand terminal of battery G, through polar contact 2 of relay E in its normal position, reverse lever contact R^L, and lock magnet L to battery G. Magnets R and L being energized, switch A will be moved to its reverse position. As soon as the switch begins to move, pole-changer C will become opened so that relay E will become de-energized. Another branch of the circuit for lock magnet L will then become closed, which branch includes the neutral back point contact 1 of relay E but excludes the polar contact 2 and the lever contact R^L. When the switch reaches its reverse position, pole-changer C will again become closed but relay E will be energized in the reverse direction so that polar contact 2 will be swung to the right. Both branches of the circuit for lock magnet L will then be opened, so that this magnet will become de-energized and will lock the switch mechanism in its reverse position.

Assuming now that lever F is restored to its normal position, the circuit for the reverse magnet R will become opened at lever contact R^A, and the circuit for the normal magnet N will become closed at lever contact N^A. A third branch for the circuit of lock magnet L will then become closed, so that this circuit passes from battery G through polar contact 2 in the reverse position, normal contact N^L of lever F, and magnet L to battery G. During the transit of the switch A, relay E will be de-energized as before, so that lock magnet L will be energized through the back neutral contact 1 of this relay. When the switch reaches its full normal position, relay E will again become energized in the normal direction, so that lock

magnet L will become de-energized and the switch mechanism will be locked in its normal position.

Located in the interlocking tower adjacent to the lever F is an indicating lamp H, which lamp is connected with the circuit for the lock magnet L and is in multiple with this magnet. It follows that the lamp H is lighted when magnet L is energized, and extinguished when the magnet is de-energized. When the lever F is operated to cause a movement of switch A, lamp H immediately becomes lighted and remains lighted until the switch responds by a complete movement, that is, until the indication relay again becomes energized. In other words, this lamp is lighted whenever the lever and the switch do not harmonize in position.

One feature of my invention is the fact that the lock magnet L becomes energized the instant that the control lever F is operated, and remains energized until the indication relay E responds to a complete movement of the switch, whereupon the lock magnet immediately becomes de-energized.

Another feature of my invention is that the switch mechanism is self-restoring at all times. For example, if the switch mechanism is operated by hand, or the valves are manually manipulated to reverse the switch while the lever F remains in its normal position, then when the manual influence is removed, the switch will immediately restore itself to the normal position. The reason for this is, that the circuit for the normal magnet N is closed at lever contact N^A, while the circuit for the lock magnet L is closed at lever contact N^L and polar contact 2 of relay E in the reverse position. Similarly, if the lever F is in the reverse position and switch A is caused by manual influence to move to its normal position, then as soon as such manual influence is removed the switch will automatically restore itself to the reverse position.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a railway switch, operating mechanism for said switch comprising a normal and a reverse magnet as well as a lock magnet, a manually operable lever provided with normal and reverse contacts, means for energizing said normal or said reverse magnet according as said normal or reverse lever contacts are closed, a polarized indication relay controlled by said switch, and a circuit for said lock magnet having two branches in multiple, one of which

branches includes a normal contact of said indication relay and a reverse lever contact in series, and the other of which branches includes a reverse contact of said indication relay and a normal lever contact in series.

2. In combination, a railway switch, operating mechanism for said switch comprising a normal and a reverse magnet as well as a lock magnet, a manually operable lever provided with normal and reverse contacts, means for energizing said normal or said reverse magnet according as said normal or reverse lever contacts are closed, a polarized indication relay controlled by said switch, and a circuit for said lock magnet having three branches, one of which branches includes a normal polar contact of said indication relay and a reverse lever contact, the second of which branches includes in series a reverse polar contact of said indication relay and a normal lever contact, and the third of which branches includes a back neutral contact of said indication relay.

3. In combination, a railway switch, operating mechanism for said switch comprising a lock magnet, a manually operable lever provided with normal and reverse contacts, a polarized indication relay controlled by said switch, and a circuit for said lock magnet having two branches in multiple, one of which branches includes a normal contact of said indication relay and a reverse lever contact in series, and the other of which branches includes a reverse contact of said indication relay and a normal lever contact in series.

4. In combination, a railway switch, operating mechanism for said switch comprising a lock magnet, a manually operable lever provided with normal and reverse contacts, a polarized indication relay controlled by said switch, and a circuit for said lock magnet having three branches, one of which branches includes in series a normal polar contact of said indication relay and a reverse lever contact, the second of which branches includes in series a reverse polar contact of said indication relay and a normal lever contact, and the third of which branches includes a back neutral contact of said indication relay.

5. In combination, a railway switch, operating mechanism for said switch comprising a lock magnet, a manually operable lever provided with normal and reverse contacts, a polarized indication relay controlled by said switch, a circuit for said lock magnet having two branches in multiple, one of which branches includes a normal contact of said indication relay and a reverse lever contact in series, and the other of which branches includes a reverse contact of said indication relay and a normal lever contact in series, and an indication lamp connected in multiple with said lock magnet.

6. In combination, a railway switch, op-

erating mechanism for said switch comprising a lock magnet, a manually operable lever provided with normal and reverse contacts, a polarized indication relay controlled by said switch, a circuit for said lock magnet having three branches, one of which branches includes in series a normal polar contact of said indication relay and a reverse lever contact, the second of which branches includes 5 in series a reverse polar contact of said indication relay and a normal lever contact, and the third of which branches includes a back neutral contact of said indication relay, and an indication device connected in multi- 10 ple with said lock magnet.

In testimony whereof I affix my signature.
JOHN E. McCARLLEY.
